(Cl. D57—1)

To all whom it may concern:

Be it known that I, Ernst Fuchs, of German nationality, residing at 35 Barn Rise, Wembley Park, in the county of Middlesex, England, have invented a new, original, and ornamental Design for a Profile Testing Eyepiece Unit for Attachment to a Microscope, of which the following is a specification, reference being had to the accompanying drawing, forming part thereof, in which:

Fig. 1 is a side perspective view of a profile

testing eyepiece unit for attachment to a microscope of my new design.

Figure 2 is a perspective view of the same from the opposite side.

Figure 3 is a side elevation of the same.

I claim:

The ornamental design for a profile testing eyepiece unit for attachment to a microscope, as shown.

ERNST FUCHS.
